UNITED STATES PATENT OFFICE.

SALVATORE D'APREA, OF BROOKLYN, NEW YORK.

SHOE-POLISHING MACHINE.

Application filed May 7, 1923. Serial No. 637,212.

To all whom it may concern:

Be it known that I, SALVATORE D'APREA, a subject of the King of Italy, and a resident of the borough of Brooklyn, county 5 of Kings, city of New York, and State of New York, have invented a new and Improved Shoe-Polishing Machine, of which the following is a full, clear, and exact description.

10 This invention relates to an improved shoe polishing machine of the hand supported and directed type embodying certain novel features very desirable in the shoe polishing trade.

15 An object of the invention is that of providing a polishing machine having a pair or more of adjacent polishing elements simultaneously moving in opposite directions with respect to each other in order to subject the surface or shoe to be polished to oppositely directed rubbing action as subjected by the back and forth rubbing strokes of the ordinary hand brush.

20 Another object of the invention is that of bringing forth a light, simple and manageable polishing machine characterized more particularly by its capability of causing an opposite rubbing action on a surface to be polished without changing the direction of 25 its moving parts or the general disposition of the machine.

25 Still another object of the invention is that of constructing a simple and durable hand supported polishing machine, the 30 polishing elements of which are adapted to produce upon a surface to be polished a rubbing effect in opposite directions by merely moving the surface to be polished or the machine laterally with respect to 35 one another.

40 Further objects together with the advantages of the device will appear in the specification of which the accompanying drawings form a part, it being understood that 45 the drawings illustrate only an embodiment of the invention to which I do not limit myself since the same could be varied without departure from the spirit of the invention.

50 Figure 1 is a perspective view of the shoe polishing machine disclosing one embodiment of the invention.

55 Figure 2 is a longitudinal sectional view of the device through the medial plane of the device and showing the driving mechanism thereof.

60 Figure 3 is a longitudinal sectional view

of one of the brushes taken on line 3—3 of Figure 1.

Figure 4 is also a longitudinal sectional view of the device taken on line 4—4 of 60 Figure 3 and showing the mechanism for clutching a fixable drive shaft to the driving shaft of the machine.

Figure 5 is a figure similar to Figure 4 but showing a modification thereof wherein 65 a friction drive is substituted for the gear drive.

There is a great variety of shoe shining and polishing machines on the market but so far as I am aware of, they fail to fully 70 produce the luster effect of a shine obtained by the back and forth rubbing strokes of an ordinary hand brush. The luster on a shoe or boot can best be obtained by rubbing the surface of the shoe in back and 75 forth strokes, under which action the blacking or polishing paste spread on the surface of the shoe is more quickly dried and the pulverulent ingredients thereof scoured 80 off the shoe instead of being pressed or coated on the surface of the shoe to form thereon a coating which, after the shoe has been bent few times by walking, cracks and 85 renders the appearance of the shoe rather unsightly. Being aware of the above mentioned necessities and difficulties, and being 90 aware of the strenuous labor expended in polishing shoes with ordinary hand brushes, I have resorted to the present invention in order to mechanically produce a rubbing 95 action on the shoe as produced by the back and forth strokes of the ordinary hand brush, and in order to further speed up the drying process of the blacking spread on the shoe by creating an air flow about the 100 shoe by the opposite rotation of the rubbing and polishing members of the device, to say the least of the quickness with which the shoe may be polished by a mechanical device and especially by one constructed in accordance with my invention.

105 In the drawings a frame member 1 formed with a nipple 2, the outer face of which is threaded as at 3, conveniently carries by means of side members 4 and 5, a transversely extending shaft 6 which is supported by said side members. The side members 4 and 5 are secured to the frame 1 by means of screws or any other approved means 7, 110 and are each formed with an opening 8 at their free or inner ends in which fit the ends of the shaft 6. The ends of shaft 6

are threaded as at 9 for receiving the nuts 10 for securing the said shaft against lateral movement.

Preferably a reinforcing member 11 is secured, in any approved manner, to the central portion of the frame 1 and from there it extends inwardly to a point substantially in the plane of the lower ends of the members 4 and 5. This member 11 is formed at its lower end with a threaded bore 12 for receiving the threads 13 of the shaft 6 for preventing lateral movement of the member 11. By means of the above described arrangements, it will be noted that a strong unitary structure is formed between the frame 1, the shaft 6, and the members 4, 5 and 11.

As shown in Figures 4 and 5, the reinforcing member 11 presents a slot 14 for accommodating a portion of the shaft 15 and the pinion 16 carried at the end of the shaft 15. Advantageously the member 11 may provide, adjacent the pinion 16, a bearing recess 17 in which a bearing 18 is accommodated for providing a bearing for the inner end of the shaft 15. The shaft 15 has bearing in the frame member 1 by means of ballbearing or any other kind of bearing 19, and extends to a point outwardly of the nipple 2, where it presents a V-slot 20. The shaft 15 is thus arranged for rotation in the frame of the device by means of end bearing 18 and central bearing 19.

In order to drive the shaft 15, a flexible shaft 21 is provided which runs to a motor or to any other rotative means and which at its lower end is V-shaped as at 22 for interlocking with the V slot 20 of the shaft 15. As the flexible shaft 21 is of the usual construction, and in fact any approved type may be used, a description thereof is omitted.

This shoe polishing machine is of the hand operated type, that is of the type which is supported by the hand of the operator and by him moved about the shoe or surface to be polished. For the purpose of affording a hand grip for the operator, a handle 23 is provided which has a through bore 24 threaded at its lower end as at 25 for engaging the threads 3 of the nipple 2 and presenting at its upper end an annular groove 26. By means of this handle 23, the whole polishing machine may be held and supported by an operator and moved about any object as the operator desires.

The flexible shaft 21 has fixed to the end adjacent the V shaped end 22 a clutch sleeve 27. This sleeve 27 adjacent its upper end, is formed with a longitudinal groove 28, and alongside of this groove extends a flexible tongue 29 secured to the clutch sleeve 27 by means of a screw or other suitable element 30. The tongue 29 intermediate its ends is formed with an en-

largement or catch 31, adapted to be housed in the annular groove 26. When the clutch sleeve 27 is inserted into the handle 23 the enlargement 31 snaps into the groove 26 to lock the clutch against outward movement. 70

The clutch sleeve 27 together with the flexible shaft 21 may be removed from the handle 23 by depressing the flexible tongue 29 toward the groove 28, so as to disengage the enlargement 31 from the annular groove 75 26, to permit the withdrawal of the sleeve from the handle 23. Thus the flexible shaft may be connected with a power means by merely inserting the clutch assemblage 80 to the handle 23. It will be noted that the clutch sleeve 27 is free to rotate within the bore 24 of the handle 23, the latter acting as a bearing for the former.

On the shaft 6 are mounted brush elements 32 and 33 each of which are preferably provided with bristle 35. Each of the brush elements 32 and 33 comprise an annular bristle back 36 which is formed adjacent one edge with an annular rabbet 37 in which is tightly fitted an end piece 38 90 in the center of which is mounted the bearing 39, the latter rotating adjacent the ends of the shaft 6 near the side members 4 and 5. At the opposite edge of the annular bristle backs are tightly fitted gear backs 95 40 to which are secured bevel gears 41 meshing with the pinion 16 and in the center of said gear backs are mounted bearings 42 which bear adjacent the center of the shaft 6 at the sides of center member 11. 100

The gear backs 40 may conveniently be held against an inward movement by means of pins 43 which are carried by the bristle back 36.

When the bristles of the brush elements 105 become worn out, or when another set of brushes is wished to replace those already on the device, the nuts 10 are first unscrewed, then the side members 4 and 5 are removed by removing screws 7, and then the brush elements are slid off the shaft 6 and replaced with a new set, or with a type having a cloth material instead of bristles.

From Figure 2 it will be seen that it is preferred to have the adjacent brush elements 32 and 33 as near together as possible and for this purpose the shaft 15 adjacent the pinion 16 is slightly reduced in diameter (as at 44) so as to reduce the distance between the two brush elements. 115 120

The gears 41 are not absolutely necessary to drive the brush elements 32 and 33 for a friction drive may well be substituted for the same as shown in Figure 5, where in the pinion 16 is substituted by friction cone 116 and gears 41 by a friction ring 141 which may be made of any friction material such as leather, rubber or the like.

It is thus seen by the above description, that a very simple and easily disassembled 130

hand supported polishing device has been provided, the parts of which are easily changed and replaced without the aid of machines or special tools. The whole device 5 may be removed from the flexible shaft 21 and clutch sleeve 27 and in lieu thereof another substituted for polishing different colored shoes or surfaces.

The principal advantage of the device is 10 that of having its brush elements 32 and 33 driven in opposite directions as shown by the arrows 45 in Figure 1 and as understood from the illustration in Figure 2 wherein it is seen that the pinion 16 engages 15 the gears 41 at diametrically opposite points driving the said brush elements in opposite directions. The device in operation is moved in various directions about the shoe or boot to be polished for subjecting all 20 points of the shoe to the rubbing action of both elements.

I would state in conclusion that while the 25 illustrated example constitutes a practical embodiment of my invention, I do not limit myself strictly to the mechanical details herein illustrated, since manifestly the same can be considerably varied without departing from the spirit of the invention as defined in the appended claims.

30 Having described my invention I claim:

1. In a shoe polishing device a frame, a tubular handle for holding said frame in the hand of an operator, polishing brushes carried in said frame, a driving shaft for driving said polishing brushes, a clutch sleeve connected to a power drive rotatively extending within said handle and adapted to engage said shaft, said handle adjacent its free end being formed with an annular groove, and a spring member formed with 35 an enlargement to fit in said groove secured to said clutch sleeve for locking the same in said tubular handle.

2. A shoe polishing machine comprising a transverse frame member formed with a 40 cylindrical projection at one side, a driving shaft extending through said frame member and said cylindrical projection, a pinion at the end of said shaft, a pair of side members secured to the ends of said transverse frame member, a supporting shaft supported on said side members, a pair of brush elements mounted to rotate 45 on said supported shaft and a gear associated with each of said brush elements both in mesh with said pinion, whereby said brush elements are driven by said pinion in opposite directions with respect to each other.

SALVATORE D'APREA.
